UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

MECHANISM FOR ASSEMBLING AND DISTRIBUTING TYPE.

990,584.

Specification of Letters Patent. Patented Apr. 25, 1911.

Application filed July 22, 1907. Serial No. 384,912.

To all whom it may concern:

Be it known that I, HENRY C. OSBORN, a citizen of the United States, residing at Cleveland, in the county of Cuyahoga and State of Ohio, have invented a certain new and useful Improvement in Mechanism for Assembling and Distributing Type, of which the following is a full, clear, and exact description, reference being had to the accompanying drawings.

The object of this invention is to provide a simple and efficient hand-actuated machine for assembling and distributing type.

The machine is well adapted for use in conjunction with a hand printing machine. It carries a supply of type and has hand-operative mechanism which may assemble the type in desired words in a temporary holder. The holder or the type therein, may then be transferred to the printing mechanism, and after the matter is printed, the type re-transferred to a holder, from which the present machine distributes the type into the supply member.

The invention is capable of various embodiments. It is shown herein as a small office machine using type adapted to print in imitation of typewritten matter—the various characters of such type having all the same sized body.

The invention is hereinafter more fully described and its essential characteristics set out in the claims.

In the drawings, Figure 1 is a front elevation of the machine; Fig. 2 is a vertical axial section thereof; Fig. 3 is a plan; Fig. 4 is a horizontal section substantially on the line 4—4 of Fig. 2; Fig. 5 is a detail in section on the line 5—5 of Fig. 2; Fig. 6 is a perspective of a type of the class which this particular embodiment carries.

The frame of my machine comprises a base plate 10, a top plate 11, and suitable connecting rods 12, of which three are shown, located between the base and top plate. These rods may be secured by suitable screws passing through ears on the plates.

15 represents a vertical type-carrying drum, which is rotatably mounted in the frame described. This drum is built up of rails 16, secured to the periphery of spiders 17, 18 and 19. These spiders are rigidly mounted on a central shaft 20, which is journaled in bushings 21 and 22, set onto the top

and bottom frame plates. A suitable thrust bearing is provided for the lower end of the shaft 20. This bearing is shown as a conically pointed screw 24, which is axially mounted in a depressed portion of the base plate, being adjustably locked by the jam-nut 25. On the upper end of the shaft 20 is a hand wheel 30 by which the drum may be turned to any position desired.

The rails 16, on the periphery of the drum, have overhanging edges, whereby they are adapted to confine type grooved in their sides, such type are shown individually in Fig. 6 and shown at 32 in Figs. 2 and 5.

35 indicates a temporary type-holder adapted to contain the type to be distributed. This type holder is shown as a split tube, the edges of the tube adjacent to the split being adapted to enter the grooves of the type as shown in Fig. 5. This tube 35 is carried in a partially tubular socket 28, on the forward portion of the top plate 11. Similarly, a split tube 36 for receiving the type being assembled, is carried by a partially tubular socket 29 on the front side of the base plate 10. These split tubes may be held in place by their own elasticity in their respective sockets.

With a structure as above described, it will be seen that with type contained in the tube 35, it is only necessary in distributing, to turn the drum by its hand wheel to bring the proper channel, provided by adjacent rails 16, into position, and transfer the type from the tube 35 into such channel. Similarly, in assembling, the drum is turned by the hand wheel to bring the proper channel to the front, and suitable transfer mechanism is operated to convey the type from the bottom of the drum into the assembling tube 36. These transfer mechanisms will now be described.

Slidably mounted in a radial groove 40 on the underside of the top plate 11 is a sliding plate 41. This plate is of the same thickness as the corresponding dimension of the type and has an opening 42 formed of the proper shape to receive the type. This opening is normally directly below a column of type in the carrier 35, so that the bottom type normally occupies the opening. A plate 43 below the opening prevents the type from dropping out of the slide.

The slide is normally in its outermost

position, and when shoved inward, the single type contained in the opening 42, is carried over the upper end of the type channel located beneath it, and accordingly drops into 5 that channel.

To assemble the type from the lower end of the drum into the assembling tube 36, I provide an identical slide 51 mounted in a radial groove 50 in the upper face of the 10 base plate 10. This slide has a type carrying opening 52 normally located over the channel which leads to the tube 36, this channel being provided by the pair of plates 53 carried on the front side of the base 15 plate 10. The lowest type in the drum channel which is at the front, normally rests on the top of slide 51. When the slide is pushed rearwardly, the bottom type in the drum channel drops into the opening 52, and on the return movement of this slide, 20 this type is dropped into the column for assembling.

Each of the slides 41 and 51 is normally held in its forward position by a spring 44, 25 which is secured at one end to a stationary stop 45 and at the other to a pin 46 secured to the slide. A suitable pin 47 extending through a slot 48 in the slide limits the 30 movement of the slide. A head or knob 49, is provided at the outer end of the slide, to receive the operator's thumb or finger, whereby the slide may be conveniently pushed rearwardly.

To enable the drum to be properly located for either distributing or assembling, I provide first, an indicator assisting the operator in positioning the drum, and second, locking devices to insure accurate 35 position of the drum and to hold it in such 40 position during the transfer of the type. These features will now be described.

The periphery of the hand wheel 30 is 45 preferably flattened and is provided with indicating characters, corresponding to the type in the respective channels of the drum, these indications being shown at 60 in Fig. 1. Coöperating with the characters of this indicator is a pointer 61, carried by the top plate 11. This construction enables the operator to very easily position the drum with 50 approximate accuracy.

To insure absolute accuracy, and the holding of the drum, I provide on the upper face of the spider 17, and also on the lower 55 face of the spider 19, a ring 64 having in its periphery V-shaped notches, one for each type channel. This ring may be accurately adjusted and held in position by screws 65, passing through slotted openings in the 60 ring. Coöperating with this ring is a lug 67, carried by the corresponding slide 41 or 51, and having a V-shaped nose adapted to enter any of the V-shaped notches of the ring. The drum is brought so nearly into 65 position by the hand wheel that whenever

one of the plungers 49 is actuated, a lug 67 enters the corresponding notch of the ring, accurately positioning the drum.

It will be seen from the above description, that I have provided a type case adapted 70 to contain a supply of type, and have combined this with very simple mechanism by which type may be distributed into the case or assembled from it. Simplicity and cheapness of construction are valuable 75 attributes of my machine.

This machine as shown, is adapted for embodiment in a small structure, which may conveniently stand on a table, the tube 36 overhanging the edge of the table and the 80 hand wheel being conveniently placed for the operator sitting at the table.

The machine is shown as operating with short grooved type, all having the same body, such as used on the multigraph. If 85 desired, however, the mechanism can be arranged for carrying other styles of type. If the type are of different-thickness, the slides 41 and 51 may be made of a number 90 of superimposed thin plates, as many of them operating concurrently as there are units in the type. Thus, for example, if the font of type has seven different units of body, there would be seven plates, one plate being used for the narrowest letter (i, for 95 example) and all the plates being used for the widest letter, W. With such construction, the slides and drum would carry properly positioned coöperating shoulders to bring into action the number of slides corresponding to the number of units in the body of the type which the channel of the drum in active position is designed to carry. These features may be covered in a 100 separate application hereinafter filed.

The present invention is designed to 105 cover a drum with assembling and distributing slides, whether each slide is a unitary member or a multiple member.

I claim,

1. The combination with an upright storage member adapted to hold type on their sides, a coöperating upright column type holder adapted to hold type on their sides, and a transversely operating transfer slide 115 coöperating with the two and formed with an opening to allow the type to pass through it without being axially turned.

2. The combination with a storage member adapted to hold parallel rows of type 120 on their sides, a coöperating column type holder for type on their sides, and a radially movable transfer slide coöperating with the two and having an opening adapted to hold a type on its side, the type passing into one 125 side of the slide and out of the other.

3. The combination with a storage member adapted to carry a plurality of columns of type, and a pair of transfer slides coöperating with the opposite ends of the storage 130

- member, said slides being formed with openings to allow the type to pass through them.
4. The combination with a storage member, of a transfer member coöperating therewith, and having an opening to receive a type, a spring for holding said member in one position, and a finger knob on said member for moving it.
5. The combination of a storage member 10 adapted to carry a plurality of columns of type, a transfer slide at one end of said member and a transfer slide at the other end of said member, each of said slides having an opening adapted to coöperate with a channel of the storage member.
6. The combination of an upright, channeled member adapted to carry a plurality of columns of type, a transfer slide at the upper end of said member and a transfer 20 slide at the lower end of said member, each of said slides having an opening adapted to coöperate with the channels of the storage member.
7. The combination of a rotary type holding drum, mechanism for distributing type into one end of the drum, mechanism for assembling type from the other end of the drum, and mechanism for turning the drum in either direction, as desired.
- 25 8. The combination of a rotary type holding drum mounted on a vertical axis, mechanism for distributing type into the upper end of the drum, mechanism for assembling type from the lower end of the drum, and a hand wheel for turning the drum in either direction, as desired.
- 30 9. The combination with base and top plates of a rotatable drum mounted between said plates and having longitudinal type 40 holders which are terminated by said plates, distributing mechanism carried by the top plate, and assembling mechanism carried by the base plate.
- 35 10. The combination with base and top 45 plates, of a rotatable drum mounted between said plates and having longitudinal channels which are closed by said plates, distributing mechanism carried by the top plate, assembling mechanism carried by the base 50 plate, and independent finger means for operating each of said mechanisms.
- 55 11. The combination, with two end plates, of a drum located between said plates and mounted on a shaft journaled into said plates, means for turning said shaft in either direction, as desired and a distributing and assembling mechanism mounted on said plates respectively.
- 60 12. The combination of a top plate, a base 65 plate, a rotatable drum located between said plates and mounted on a shaft journaled into said plates, and a distributing slide and an assembling slide, mounted on said plates respectively, and each having an opening adapted to receive a type.
13. The combination of a base plate and a top plate, a shaft journaled in said plates, a type carrying drum rigidly mounted on said shaft, a hand wheel rigidly connected with said shaft beyond one of said plates, and a transfer slide carried by one of said plates. 70
14. The combination of a base plate and a top plate, a vertical drum, rotatably mounted between said plates, a hand wheel beyond one of said plates connected with said drum, 75 and means carried by the top plate and base plate respectively for distributing type into the drum or assembling type from it.
15. The combination of a rotatable type-holding drum, a hand wheel for rotating it, 80 an indicator on the periphery of the hand wheel a pointer coöperating with the indicator, and means for concurrently locking the drum and feeding type to or from it.
16. The combination of a base plate and a top plate, a vertical type-holding drum rotatably mounted between them, a hand wheel for rotating said drum, an indicator on the hand wheel, a pointer coöperating with the indicator, and transfer mechanisms 90 carried by the base plate and top plate respectively.
17. The combination of a base plate and a top plate, a shaft journaled in said plates, a channeled drum rigidly mounted on said 95 shaft, the channels being open at their ends as far as the drum is concerned, but closed by said plates; a hand wheel on the far side of one of said plates rigidly connected with said shaft, an indicator on the periphery of 100 the hand wheel corresponding to the type channels of the drum, and a pointer coöperating with said indicator.
18. The combination of a base plate and a top plate, a vertical shaft journaled in said plates, a rotary type-holding drum rigidly mounted on said shaft, a hand wheel above the top plate rigidly connected with said shaft, an indicator on the periphery of the hand wheel corresponding to the type-holders of the drum, a pointer carried by the top plate, a column typeholder carried by the top plate, and a transfer slide carried by the top plate and adapted to coöperate with said column typeholder and any of a plurality 110 of typeholders on the drum. 115
19. The combination with a rotary storage drum of a column type holder with a transfer slide interposed between the two and having a type receiving opening adapted to align in one position with a channel of the drum and in another position with the column type holder. 120
20. The combination with an upright rotary channeled drum of column type holders, above and below the drum and offset from its channels, and transfer slides interposed between said type holders and drum, and each having a type receiving opening 125 adapted to align in one position with a chan- 130

- nel of the drum and in another position with the corresponding column type holder.
21. The combination with a type-holding storage drum, of another type holder out of alignment with the drum, and a transfer slide having a type receiving opening adapted to align with both type-holders.
22. The combination, with a member adapted to hold a plurality of rows of type, of another member adapted to hold a row of type out of alignment with the rows in the member first mentioned, and a transfer device comprising a slide having an opening for a single type adapted to be brought into alignment with a row in either member.
23. The combination, with a channeled storage member, of a type holder, a transfer slide interposed between the two, and having a type receiving opening adapted to align in one position with a channel of said member and in another position with said type holder, a spring tending to hold said slide in one extreme position, and a finger knob or head by which the slide may be moved to its other extreme position.
24. The combination, with a rotary, channeled, upright storage drum, of a column type holder, a transfer slide interposed between the two and having a type receiving opening adapted to align in one position with the channel of the drum and in another position with the column type-holder, a spring tending to hold said slide in one extreme position and a finger knob or head by which the slide may be moved to its other extreme position.
25. The combination, with the end plates, of a rotary drum journaled between them, and a pair of transfer slides radially mounted in the face of said end plates, adjacent to the ends of the drum, each of said slides having means for transferring type.
26. The combination, with top and bottom frame plates, of an upright rotary drum journaled between them, a pair of transfer slides radially mounted in the face of said frame plates, adjacent to the ends of the drum, each of said slides having an opening for transferring type.
27. The combination, with the top and bottom frame plates, of a rotary drum journaled between them, a pair of transfer slides radially mounted on the face of said frame plates, adjacent to the ends of the drum, each of said slides having an opening to receive type, and column type holders, adapted to align with said openings at a time when the openings are out of alignment with a channel of the drum.
28. The combination of a base plate, a top plate and distance rods connecting them, of a vertical shaft journaled in said plates, a hand wheel on the shaft above the top plate, a drum on the shaft between the plates, said drum having type channels on its surface parallel with its axis, mechanism for distributing type into the upper end of said channels, and mechanism for assembling type from the lower end of said channels.
29. The combination of a base plate, a top plate, a vertical shaft journaled in said plates, a hand wheel on the shaft above the top plate, a drum on the shaft between the plates, said drum having type channels on its surface parallel with its axis, a slide carried by the top plate for distributing type into the upper end of said channels, and a slide carried by the base plate for assembling type from the lower end of said channels.
30. The combination of a rotatably mounted type holding drum, a notched ring carried thereby, another type holder, a transfer slide adapted to carry type from one of such holders to the other, and a shoulder carried by said slide and adapted to coöperate with said notches.
31. The combination of a plate, a drum rotatably mounted, with its end adjacent to said plate, a transfer slide on the face of said plate, adjacent to the end of the drum, a notched ring carried by the drum near said slide, and means carried by the slide and adapted to coöperate with such notches.
32. The combination of a base plate, a top plate, a drum rotatably mounted between said plates, transfer slides on the face of the plates adjacent to the ends of the drum, notched rings carried by the drum near said slides, and means carried by the slides adapted to coöperate with such notches.
33. The combination, with a rotatable drum and radially mounted transfer slide, of a notched ring carried by the drum and a lug carried by the slide and adapted to make a beveled engagement with the ring to accurately position and hold the drum.
34. The combination of a rotatable drum, a column type-holder, a transfer slide having a recess coöperating with the drum and type holder, a notched ring carried by the drum, and a lug carried by the slide and adapted to make a beveled engagement with the ring to accurately position and hold the drum.
35. The combination with a type-holding drum of a notched ring carried thereby, a transfer slide coöperating with the drum, and means carried by the slide coöperating with the ring.
36. The combination of two type carriers located at different distances from an axis about which one of said carriers is movable, mechanism for bringing one of said carriers into the same radial plane with the other and locking it therein, and an interposed radially moving slide having a finger piece on its end.
37. The combination of a type carrier, a

- storage member having type receptacles, said carrier and receptacles being out of alinement, and a transfer member moving in a path between such members and having an opening adapted to convey type from one of said members to the other. 5
38. The combination of a channeled storage member formed with longitudinal rails to hold rows of grooved type, a coöperating type-holder out of alinement with any of said rows, and transfer mechanism adapted to engage type released from one of said members and transfer it laterally to the other member without requiring removal 10 from the machine. 15
39. The combination, with a rotary channeled type-holding drum, of plates at the ends of said drum respectively, slides guided by said plates adjacent to the ends of the 20 drum, type-holders on the opposite sides of said slides out of alinement with the channels of the drum, said slides being of a thickness equal to a single type and having an opening adapted to aline in one position 25 of the slide with said type-holders and in another position of the slide with a channel of the drum. 30
40. The combination of a storage member having means for holding a plurality of rows of type, a coöperating type-holder having means for holding a row of type, said type-holder and storage member having their ends adjacent but out of alinement, and an intermediate transfer member extending 35 cross-wise of said holder and storage member and having an opening to receive the type, and embrace its opposite sides. 40
41. The combination of a storage member having means for holding a plurality of 40 rows of type, a coöperating type-holder having means for holding a row of type, said type-holder and storage member having their ends adjacent but out of alinement, and a transfer member; extending crosswise of 45 said holder and storage member, having an opening to receive the type, said transfer member adjacent to the opening having a thickness equal to the thickness of a single type. 50
42. The combination with a type-holder having means to enter the groove of grooved type, a storage member having a plurality of similarly acting typeholders, the type-holder first mentioned and those of the storage 55 member being at different distances from a definite line, and an intermediate transfer slide having an opening to embrace a single type, whereby grooved type may be held in the machine and transferred from one member to the other though intermediately free from both without being released. 60
43. The combination with a storage member adapted to hold type, a coöperating column type holder, and a transfer slide operating between the two and having an 65
- opening dimensioned to confine type therein and having a thickness equal to that of a single type. 70
44. The combination of two type-holders out of alinement, an interposed slide having a thickness equal to the thickness of a single type, said slide having an opening adapted to convey a type from one holder to the other, and a stop below the slide to prevent type falling through the opening. 75
45. The combination, with a type storage member, of a pair of slides coöperating with opposite ends thereof, each of said slides having a thickness equal to that of a single type and having an opening for moving such type cross-wise at the end of the storage member. 80
46. The combination, with a temporary type-holder, of a rotary, type-holding channeled drum, and a slide operating between the two and having an opening adapted to aline with the temporary holder or with a channel of the drum, said slide being of a thickness equal to a single type. 85
47. The combination, with two type-holders, of a slide for transferring type from one to the other, said slide having a thickness equal to a single type and having an opening formed to confine type, and a member below the slide which prevents such type falling through the opening. 90
48. The combination of a rotatable drum, finger operating mechanism for distributing type into one end thereof, and finger operated mechanism for assembling type from the other end thereof, each of said mechanisms including a slide having an opening adapted to embrace a type. 95
49. The combination of an upright rotatable drum, a hand wheel for rotating it, finger operated mechanism for distributing type into the upper end thereof, and finger operated mechanism for assembling type from the lower end thereof. 100
50. The combination of a storage drum, hand means for rotating the same, a finger operated distributing plunger at one end thereof, and a finger operated assembling plunger at the other end thereof, each plunger having an opening adapted to embrace a type. 110
51. The combination of a storage member adapted to carry a plurality of columns of type, a transfer slide adapted to coöperate with any of a plurality of such columns, and mounted on one end of said member, and a similar transfer slide at the other end of said member. 115
52. The combination with two upright type holders parallel but out of alinement, of an interposed slide movable transversely, an opening in said slide adapted to entrain type, and means below the slide and below the uppermost type holder adapted to prevent type therefrom dropping through such opening, whereby type from the upper- 125
- 130

most type holder may drop into the opening, be transferred laterally by the slide, and then drop into the lowermost type holder.

53. The combination of a top plate, a base plate, a rotatable drum located between said plates and mounted on a shaft journaled in said plates, and distributing mechanism and assembling mechanism mounted on said plates respectively and having independent 10 finger actuated means.

54. The combination of a shaft, a drum thereon, end plates for the drum in which the shaft is journaled, distance rods connecting said end plates, a hand wheel on the 15 shaft beyond one of the end plates, said drum having on its surface carriers for rows of type parallel with its axis, and mechanism for distributing type into one end of such carriers, and mechanism for assembling type 20 from the other end of such carriers.

55. The combination with a font of type grooved on its opposite sides, of a holder therefor comprising a drum with longitudinal rails on its periphery, adjacent rails 25 providing between them channels for holding the type, distributing mechanism at one end of such drum, assembling mechanism at the other end, and means for rotating the drum to present any desired channel to the 30 distributing or assembling mechanism.

56. The combination with a font of type grooved on its opposite sides, of a holder therefor comprising a drum with longitudinal rails on its periphery, adjacent rails 35 providing between them channels for holding the type, distributing mechanism at one end of such drum, assembling mechanism at the other end, said distributing mechanism and assembling mechanism each comprising a 40 laterally movable slide having an opening adapted to receive a type, said slide being adapted to be moved by the operator's finger in one direction and by a spring in the opposite direction to bring the type into or out 45 of alignment with the corresponding channel of the drum.

57. The combination of a rotary channeled storage member adapted to hold rows of type, a coöperating typeholder for an individual row, transfer mechanism adapted to engage type released from one of said members and transfer it to the other member, and means for locking the rotary member at such time.

58. The combination of an upright rotatable drum, a column typeholder, a transfer mechanism coöperating with the drum and typeholder, a notched ring carried by the drum, and a lug carried by the transfer mechanism and adapted to make a beveled engagement with the ring to accurately position and hold the drum.

59. The combination, with a rotary type storage member, of a pair of mechanisms 120 coöperating with opposite ends thereof, each

of said mechanisms being formed to hold a single type, and operating respectively to transfer the same to or from a position beyond the end of said member.

60. The combination, with a rotary type 70 storage member, of a pair of finger mechanisms coöperating with opposite ends thereof, each of said mechanisms being formed to hold and transfer a single type, and a hand wheel for rotating the storage member. 75

61. The combination of a rotary type-holding drum, provided with parallel rails for holding rows of grooved type, finger operated mechanism for distributing type into one end of said drum, and independent 80 finger operated mechanism for assembling type from the other end of it.

62. The combination of a rotary type-holding drum, finger operated mechanism for distributing type into one end of it, independent finger operated mechanism for assembling type from the other end of it, and hand operated means for rotating the 85 drum.

63. The combination of a rotary typeholding drum, finger operated mechanism for distributing type into one end of it, independent finger operated mechanism for assembling type from the other end of it, and means for automatically locking the drum 90 when either finger mechanism is operated. 95

64. The combination of a railed structure adapted to hold parallel rows of grooved type arranged about an axis, means for turning such structure about such axis, a removable holder for a single row of type, and means adjacent to one end of the railed structure 100 for receiving the end of the removable holder in juxtaposition therewith.

65. The combination of a railed structure 105 adapted to hold parallel rows of grooved type arranged about an axis, means for turning such structure about such axis, a removable holder for a single row of type, means adjacent to one end of the railed structure 110 for receiving the end of the removable holder in juxtaposition therewith, and mechanism for causing the transfer of type from one of such holders to the other.

66. The combination of a railed structure 115 adapted to hold parallel rows of grooved type arranged about an axis, means for turning such structure about such axis, a removable holder for a single row of type, means adjacent to one end of the railed structure 120 for receiving the end of the removable holder in juxtaposition therewith, and finger-operated mechanism for transferring type from the removable holder to the railed structure. 125

67. The combination of a rotatable shaft, mechanism thereon formed to hold parallel overhanging rails which may be moved by the rotation of said shaft, a temporary typeholder comprising a split tube formed to hold a single row of type, and a stationary 130

guide for said tube adapted to engage it near the exit end and insure proper presentation to the railed structure, adjacent rails and the edges of the split tube being adapted 5 to enter grooves formed in the opposite sides of each type.

68. The combination of a rotatable shaft, mechanisms thereon formed to hold parallel overhanging rails which may be moved by 10 the rotation of said shaft, a temporary type-holder comprising a split tube formed to hold a single row of type, a stationary guide for said tube adapted to engage it near the exit end and insure proper presentation to the 15 railed structure, adjacent rails and the edges of the split tube being adapted to enter grooves formed in the opposite sides of each type, and a laterally movable transfer slide having an opening to receive the type from 20 the temporary holder and deliver it to the railed structure, said slide being adapted to engage the type as it leaves the temporary holder and retain its engagement until the type passes into the railed structure.
- 25 69. The combination with two typeholders, of an intermediate movable transfer

slide provided with an opening transverse to the direction of movement of the slide, said opening being adapted to engage a type as it leaves the grasp of one holder and retain such engagement until the type passes into the grasp of the other holder, the type intermediately being out of the grasp of both holders but in the grasp of the slide opening.

30 70. The combination with two typeholders, of an intermediate movable transfer slide provided with an opening transverse to the direction of movement of the slide, said opening being adapted to engage a type 35 as it leaves the grasp of one holder and retain such engagement until the type passes into the grasp of the other holder, the type intermediately being out of the grasp of both holders but in the grasp of the slide opening, 40 and a finger key for operating said slide.

In testimony whereof, I hereunto affix my signature in the presence of two witnesses.

HENRY C. OSBORN.
